HAND TAPPING MACHINE

John C. Haugeland, Rockford, Ill.

Application September 28, 1950, Serial No. 187,290

11 Claims. (Cl. 10—139)

1

This invention relates to a new and improved hand tapping machine, designed more particularly for use on a conventional drill press, although the same is also adapted to be used as a hand tapping attachment on a lathe, arbor press, vertical mill, and other machine tools.

The principal object of my invention is to provide a precision hand tapper that is simple in construction and easy to operate and will speed up tapping and greatly reduce if not eliminate tap breakage, even when used by more or less unskilled men, and thus fill a great need in tool and die shops, machine shops, and elsewhere.

A salient feature of my improved device is the novel arrangement of compression springs inside the handwheel hub on opposite sides of a floating bushing between the hub and the thrust spindle that is mounted in the chuck, the floating bushing having a slip fit on the spindle and inside the hub, and, by virtue of its far spacing relative to the fixed bushing at the top of the handwheel hub, providing much closer accuracy of alignment, which is so important in a device of this kind. The springs thereby serve the double purpose of positioning the floating bushing and spring loading the tap for the tapping operation.

Another important feature of my improved device is the spring pressure pad slideable in the handwheel bore above the rotary locking pin and having an embossed central portion projecting downwardly to ride on the diametrically opposite sides of either of the flats provided on the pin so as to hold the pin releasably against turning accidentally from a locked position locking the tap holding adapter in the hub, the marginal portion of the pad resting on top of the tap holding adapter so as to transmit pressure to the adapter instead of the locking pin when and if the end of the spindle comes into contact with the pad in the setup operation preliminary to the performance of a tapping operation, the locking pin being of cylindrical form except for the milled off flats provided on the diametrically opposite sides of its intermediate portion so as to permit entry thereof edgewise through the narrow end of a keyhole slot provided therefor in the end of the tap holding adapter, after which the pin is adapted to be turned 90° to lock the adapter in place. Still another important feature is the novel form of adapter chuck itself, and the novel locking means therefor.

The invention is illustrated in the accompanying drawings, in which—

Fig. 1 illustrates the preferred design of my improved device and is a view partly in front 55

2

elevation and partly in vertical section on the broken line 1—1 of Fig. 2;

Fig. 2 is a plan view;

Fig. 3 is a view partly in side elevation and partly in vertical section on the broken line 3—3 of Fig. 2;

Figs. 4, 5 and 6 are two side views and an end view, respectively, of the tap holding adapter chuck, and

Fig. 7 is a view similar to Fig. 1 showing a modified or alternative construction.

Similar reference numerals are applied to corresponding parts in these seven views.

Referring first to Figs. 1 to 3, the reference numeral 8 designates the hardened steel spindle which is accurately ground to cylindrical form and provides a projecting shank portion 9 for entry and fastening in the usual way in the chuck 10 of a drill press, for example, the rest of the spindle serving as a pilot or guide 11 for entry freely in the bore 12 of a sleeve 13, forming the hub of a handwheel 13a. The latter is preferably of cast aluminum alloy for lightness and easier operation, and the bore 12 is, of course, accurately machined, inasmuch as the accuracy of alignment of the tap holding adapter chuck or tool holder 14 with respect to the spindle 8 depends to a large extent upon the accuracy with which bushings 15 and 16 fit in this bore, as well as upon the spindle 8. Bushings 15 and 16 are preferably of cast bronze and, of course, are also accurately machined to a precision fit, bushing 15 having a press fit in bore 12 and a close working fit on spindle 8, whereas bushing 16 has a close working fit externally in bore 12 and internally on spindle 8. A groove 17 is provided in spindle 8 to receive a split snap ring 18, which serves as an abutment for a washer 19, neither of which is large enough in diameter to contact the bore 12. Washer 19 serves as an abutment for the upper one of two coiled compression springs 20 and 21 received loosely in the bore 12 on opposite sides of the floating bushing 16. The springs 20 and 21 are of oil tempered spring wire and have their ends cut off squarely and ground smooth for smooth sliding action on the parts abutting the same. A spring pressure pad 22 in the form of a hardened steel washer or plate has a free fit peripherally in bore 12 and serves as the abutment for the lower end of the lower spring 21. A locking pin 23 of hardened steel is of cylindrical form at both ends so as to fit rotatably in bearing holes 24 provided therefor in hub 13 on diametrically opposite sides of bore 12, an acorn nut 25 being threaded on one end,

which is suitably reduced and threaded for this purpose, as indicated at 27, and an operating handle 28 being suitably affixed to the other end. The lower portion of hub 13 is of square section, as indicated in Fig. 2, and flats 29 are machined on diametrically opposite sides of the hub 13 for smooth working abutment by the nut 25 and handle 28. Parallel flats 30 are machined on diametrically opposite sides of the intermediate portion of pin 23, equivalent in length to the diameter of bore 12, for interlocking engagement in a keyhole slot 31 provided diametrically of the end of each of a series of tap holding adapters 14, each tap 32 of a set having its own adapter attached, so that different sized taps can be used without the loss of time and inconvenience that would otherwise be involved in removing and inserting different taps used in one adapter.

The adapters or tool holders 14 are cylindrical, as illustrated in Fig. 6, and of hardened steel, accurately ground to fit closely in the lower end of bore 12. An axial hole 33 is provided in the lower end of each adapter below a square axial bore 34 in which the square end of the shank of the tap is adapted to be entered, as shown in Figs. 1 and 3. A transverse hole 35 in the lower end of the adapter receives a set screw 36 for fastening the tap in place in the adapter.

In operation, the mechanic, having drilled the proper sized hole 37 in the piece of work 38, does as follows to tap the hole: Spindle 8 is first entered and secured in the chuck 10 of the drill press, or other machine tool. Then, the proper sized tap 32 is selected and its adapter or tool holder 14 is entered in the lower end of bore 12 of hub 13 and locked in place by pin 23, the flattened portion of the pin being entered edgewise in the narrow end of the keyhole slot 31 and the pin being then turned 90° to lock the adapter or tool holder securely in place. The downwardly projecting embossed central portion 40 of pad 22, which is raised slightly against pressure of springs 20 and 21 by the round portion of pin 23 when the pin is turned to move the flat portion to a vertical position for entry edgewise in slot 31, 45 rides back under spring pressure onto the flat portion when the pin 23 is turned 90° to locking position, thereby serving to hold the locking pin releasably in locked position, so that there is no danger of the adapter 14 being accidentally released. The downward projection of the handle 28 is the position the handle would gravitate to and this, of course, also helps to insure the pin 23 staying in locked position. The pad also serves to protect the locking pin from damage in the event a mechanic lowers the drill press spindle too far; in that event the end of the spindle strikes the pad which, in turn, transfers the thrust to the adapter. It is in this operation that it is important that the spindle be large in diameter in relation to the width of the narrow upper end of the keyhole slot in the adapter, so that the pad or plate 22 is not distorted by the spindle pressure while such pressure is brought to bear on the locking pin 23. Instead, all spindle pressure is on the adapter. When the tap is locked properly, the drill press spindle can be lowered until the tap just touches the work. Then the reading (in inches) on the drill press depth scale should be taken. Next, the tap 32 is aligned with the hole 37 to be tapped, and the drill press spindle is lowered to the former reading plus the nominal diameter of the tap. That is, if the scale reads 2" in the previous step, the spindle should be lowered $\frac{1}{4}$ " so the scale reads $2\frac{1}{4}$ " if the tap is a 75 spindle, whereby the latter is adapted to serve as

$\frac{1}{4}$ " tap, or $2\frac{1}{8}$ " for a $\frac{7}{8}$ " tap, etc. Then the drill press spindle is locked. The lowering of the spindle causes hub 13 and bushing 15 to ride upwardly on the spindle 8; this compresses the springs 20 and 21 enough to give the tap the right amount of axial thrust required to start cutting a thread, the springs being calculated to give such results for any size of hole in a selected material, like, for example, mild steel. By this method of gauging the axial force exerted by the springs 20-21 on the tap necessary to make it start cutting a thread, good results are insured and breakage of taps avoided. Under no circumstances will the mechanic ever lean on the handwheel to start the tap in the hole. Now, the wheel 13a is turned a few revolutions to engage the tap, and then the drill press spindle lock is released. The drill press spindle will be forced up by its own return spring and by the springs 20-21 in the tapper. The reading on the drill press depth scale minus the original reading taken will show the exact depth to which the tap has penetrated the work. It should be noted that the drill press spindle, belt, motor, etc., do not turn 25 when the handwheel 13a is turned. Consequently, the mechanic has a better "feel" in the progress of the tap in tapping and it requires less real work to do the tapping. The tapping is continued by further turning of the handwheel 13a until the tap has penetrated the desired distance (blind tapping) as indicated on the drill press depth scale. Finally, the tap is released from the work by turning the handwheel 13a in the reverse direction, after which the spindle 8 is removed from the chuck 10, unless, of course, another or other holes are to be tapped. If another sized tap is required for a second hole, the first adapter is removed and the adapter having the desired tap in it is substituted. Close accuracy 30 of alignment of the tap with the spindle is assured by providing the floating bushing 16 between the two springs 20 and 21, because this bushing is, therefore, spaced to a maximum extent relative to bushing 15. Due to its floating in the bore 12, the bushing 16 does not interfere with the functioning of the springs, the latter shifting the bushing downwardly in hub 13 to a small extent to maintain a mid-position between washer 19 and pad 22 when the springs are compressed by the lowering of the drill press spindle, as above described, thereby giving the maximum spacing of bushing 16 relative to bushing 15 for maximum accuracy of guiding function under all operating conditions.

55 In the modified form shown in Fig. 7 the same general construction is used but there is only one coiled compression spring 20' between a bushing 16' and the pad 22, the bushing 16' having a press fit on spindle 8 and a close working fit in bore 12.

The mode of operation of this device is the same, but, due to the closer spacing of bushings 15' and 16', the accuracy of alignment is not as close.

60 It is believed the foregoing description conveys a good understanding of the objects and advantages of my invention. The appended claims have been drawn to cover all legitimate modifications and adaptations.

65 I claim:

1. A device of the character described comprising a spindle, one end portion of which is adapted to be gripped in a chuck, a sleeve surrounding the major portion of the rest of the length of said spindle, whereby the latter is adapted to serve as

a guide therefor, manually operable handle means on the sleeve for turning the same, said sleeve having an accurately formed bore provided therein larger in diameter than said spindle, whereby to provide space for spring means between said parts, means on the sleeve defining a reduction in diameter of the bore at the upper end to form a guide bearing slidable on the spindle, coiled compression spring means surrounding said spindle inside said sleeve and disposed in downwardly spaced relation to said guide bearing, the lower end of the bore being adapted to mount therein a tool holder carrying a tap in coaxial relation to said spindle, means on the sleeve adapted for locking a tool holder in the sleeve against turning and against displacement relative to the sleeve, said means being formed to provide a retaining abutment for the lower end of said spring means when the tool holder is removed, and means surrounding the spindle providing another abutment for said spring means and a guide bearing for the sleeve on the spindle in downwardly spaced relation to the first mentioned guide bearing but above the tool holder locking means, whereby when the spindle is moved downwardly relative to said sleeve said spring means is compressed to exert end thrust on the tool holder in proportion to the compression.

2. A device as set forth in claim 1, wherein the means surrounding the spindle providing another abutment for said spring means and a guide bearing for the sleeve on the spindle comprises a bushing fixed internally to the spindle and having a close working fit externally in the bore in said sleeve.

3. A device as set forth in claim 1, wherein the coiled compression spring means comprises two coiled springs surrounding the spindle, the device including a spring abutment fixed on the spindle engaging the upper end of the upper one of said springs to prevent upward displacement thereof, the means surrounding the spindle providing another abutment for said spring means and a guide bearing for the sleeve on the spindle comprising a bushing slidable closely on the spindle and disposed between and abutting the adjacent ends of the two springs and having a close sliding fit inside the sleeve and on the spindle.

4. A device of the character described comprising a spindle, one end portion of which is adapted to be gripped in a chuck, a sleeve surrounding the major portion of the rest of the length of said spindle, whereby the latter is adapted to serve as a guide therefor, manually operable handle means on the sleeve for turning the same, said sleeve having an accurately formed bore provided therein larger in diameter than said spindle, whereby to provide space for spring means between said parts, means on the sleeve defining a reduction in diameter of the bore at the upper end to form a guide bearing slidable on the spindle, coiled compression spring means surrounding said spindle inside said sleeve and disposed in downwardly spaced relation to said guide bearing, means surrounding the spindle in downwardly spaced relation to said guide bearing providing one abutment for said spring means and a guide bearing for the sleeve on the spindle, and a locking pin extending diametrically of the lower end portion of said sleeve adapted to serve as another abutment for said spring means and prevent displacement thereof from the sleeve, the lower end of the bore being adapted to mount therein a tool holder carrying a tap in coaxial relation to said spindle, said locking pin being adapted for de-

tachable connection with the end of the tool holder to secure it against turning and against displacement relative to the sleeve, the assembly as described caging said spring means so that when the spindle is moved downwardly relative to said sleeve said spring means is compressed to exert end thrust on the tool holder in proportion to the compression.

5. A device of the character described comprising a spindle, one end portion of which is adapted to be gripped in a chuck, a sleeve surrounding the major portion of the rest of the length of said spindle, whereby the latter is adapted to serve as a guide therefor, manually operable handle means on the sleeve for turning the same, said sleeve having an accurately formed bore provided therein larger in diameter than said spindle, whereby to provide space for spring means between said parts, means on the sleeve defining a reduction in diameter of the bore at the upper end to form a guide bearing slidable on the spindle, coiled compression spring means surrounding said spindle inside said sleeve and disposed in downwardly spaced relation to said guide bearing, means surrounding the spindle in downwardly spaced relation to said guide bearing providing one abutment for said spring means and a guide bearing for the sleeve on the spindle, a circular plate slidable up and down in the lower end of the bore providing another abutment for said spring means, a rotary cylindrical locking pin extending diametrically of the lower portion of said sleeve immediately under said plate and rotatably received in bearing holes provided therefor in the sleeve thus preventing displacement of the plate and spring means from the sleeve, said pin having portions on its diametrically opposite sides cut away to define flats on opposite sides of a reduced portion that is adapted to be received in the end of a tool holder to secure it against turning and against displacement relative to the sleeve, the lower end of the bore being adapted to mount therein a tool holder carrying a tap in coaxial relation to said spindle, said plate having a downwardly projecting central portion arranged to engage either of the flats on the pin under spring pressure and hold it releasably in locked position, the assembly as described caging said spring means so that when the spindle is moved downwardly relative to said sleeve said spring means is compressed to exert end thrust on the tool holder in proportion to the compression.

6. A device as set forth in claim 5, wherein means for turning the pin comprises a handle fixed to and extending radially relative to one end of said pin and arranged so as to be in a pendant relation to the end of said pin when the pin is in locking position, whereby gravity assists in holding the pin releasably in locked position.

7. In combination, a tool holder sleeve having a cylindrical bore, an adapter chuck for mounting a tool, such as a tap, comprising a cylindrical body adapted to be entered with a close fit in the open end of said bore and having an axial bore in the lower end adapted to receive the shank of the tool, said cylindrical body having provided in its upper end a keyhole-shaped slot diametrically thereof with the small end open to the top of said body, a cylindrical locking pin extending diametrically of the lower portion of said sleeve and rotatably received in bearing holes provided therefor in the sleeve, said pin having portions on its opposite sides cut away to define a reduced portion which is thin enough to permit entry thereof edgewise through the small end of said

keyhole slot, the wider portion of said slot being of approximately the same diameter as said pin, means for turning said pin to and from locking position in the wider portion of said slot, and a coiled compression spring housed in the sleeve in compressed condition and bearing at its lower end on a plate that is slidable in the sleeve normal to the axis thereof and arranged to rest on the pin when the adapter chuck is removed, said plate having a downwardly projecting central portion engageable with either of the flats on the pin under spring pressure through the narrow portion of the keyhole slot to hold the pin releasably in locking position.

8. The combination set forth in claim 7, including a guide spindle coaxially arranged with respect to the sleeve and slidably engaged in the upper end of the bore and disposed in telescoping relation to the coiled compression spring, the diameter of said spindle being greater than the width of the narrow portion of the keyhole slot, so that if the spindle is moved downwardly into abutment with the plate, during a tapping operation, for example, the thrust is transmitted to the adapter without deflection of the plate and substantially independently of the locking pin.

9. In combination, a tool holder sleeve having a cylindrical bore, an adapter chuck for mounting a tool, such as a tap, comprising a cylindrical body adapted to be entered with a close fit in the open end of said bore and having an axial bore in the lower end adapted to receive the shank of the tool, said cylinder body having provided in its upper end a keyhole-shaped slot diametrically thereof with the small end open to the top of said body, a cylindrical locking pin extending diametrically of the lower portion of said sleeve and rotatably received in bearing holes provided therefor in the sleeve, said pin having portions on its opposite sides cut away to define a reduced portion which is thin enough to permit entry thereof edgewise through the small end of said keyhole slot, the wider portion of said slot being of approximately the same diameter as said pin, means for turning said pin to and from locking position in the wider portion of said slot, a coiled compression spring housed in the sleeve in compressed condition above the locking pin to exert pressure endwise on the adapter chuck, and a guide spindle coaxially arranged with respect to the sleeve and slidably engaged in the upper end of the bore and disposed in telescoping relation to the coiled compression spring, the diameter of said spindle being greater than the width of the narrow portion of the keyhole slot, so that if the spindle is moved downwardly to an extreme posi-

tion relative to the sleeve, during a tapping operation, for example, it exerts pressure on the adapter chuck substantially independent of the locking pin.

5 10. A device of the character described, comprising a guide spindle adapted to be mounted in a chuck and advanced toward a work piece, a tool holder normally in spaced coaxial alignment with the spindle, a sleeve slidable on the spindle as a guide and having the tool holder fixed in its one end, said sleeve providing a chamber therein around the spindle, two coiled compression springs with a bushing therebetween disposed in said chamber, the springs encircling the spindle and the bushing having a close sliding fit on the spindle and inside the sleeve, there being a shoulder on the spindle engaging the upper end of the upper spring, the lower end of the lower spring being arranged to exert pressure on the tool holder, so that the spring pressure on the tool in the tool holder varies according to the proximity of the spindle to the tool holder, and manually operable handle means on the sleeve for turning the same.

20 25 30 35 40 45 50 55 11. A device of the character described, comprising a guide spindle adapted to be mounted in a chuck and advanced toward a work piece, a tool holder normally in spaced coaxial alignment with the spindle, a rotary sleeve slidable on the spindle as a guide and having the tool holder fixed in its one end, said sleeve providing a chamber therein around the spindle, and two coiled compression springs with a bushing therebetween disposed in said chamber, the springs encircling the spindle and the bushing having a close sliding fit on the spindle and inside the sleeve, there being a shoulder on the spindle engaging the upper end of the upper spring, the lower end of the lower spring being arranged to exert pressure on the tool holder, so that the spring pressure on the tool in the tool holder varies according to the proximity of the spindle to the tool holder.
